SCISSORS

Byron L. Atchison, Kanopolis, Kans.

Application September 16, 1937, Serial No. 164,260

1 Claim. (CL. 30—260)

This invention relates to an improved scissors employing a razor blade as one of the cutting members.

An important object of this invention is to provide a device whereby new or used razor blades can be mounted in a scissors frame to provide the cutting member, and to removably mount the blade so that it can be readily replaced thereby having a scissors that at all times will be sharp and yet will never require sharpening.

A further object of the invention is to provide a device having frames mounted on corresponding ends of the scissors to support the blade and to cooperate with the blade in cutting, one frame carrying the cooperating means which also serves as a shield for the edge of the blade when in a closed position.

Another object of the invention is to provide a blade holding frame that is reversible to mount the blade for use as a scissors or as a knife.

A particular advantage of the invention resides in the fact that razor blades which are no longer of value for shaving can be used and will still be sufficiently sharp for use with this invention, thereby providing an additional use for blades which would otherwise be discarded.

Other objects and advantages of the invention will hereinafter become more fully apparent from the following specification of which the drawings form a part and wherein:

Figure 1 is a side elevational view of the invention in a closed assembled position;

Figure 2 is a similar view of the invention in an open position;

Figure 3 is a side elevational view showing the use of the invention as a knife;

Figure 4 is a cross sectional view on the line 4—4 of Figure 1;

Figure 5 is a perspective view of the blade holder;

Figure 6 is a similar view of the cooperating frame;

Figure 7 is a view similar to Figure 1 of a modified form of the invention;

Figure 8 is a cross sectional view on the line 8—8 of Figure 7;

Figure 9 is a perspective view of the modified blade holder, and

Figure 10 is a perspective view of the modified cooperating frame.

Referring more particularly to the drawings wherein like reference characters designate like or corresponding parts throughout, 10 designates

55 generally the improved scissors comprising the

members 11 and 12 which are pivoted intermediate of their ends at 13. The members 11 and 12 are provided with openings at adjacent ends forming the conventional fingerholds 14 and 15 respectively.

Referring to Figure 1, the opposite ends of members 11 and 12 are bent at their pivot point 13 to extend in substantially opposite directions to form the portions 16 and 17. These ends are then turned at right angles to form the corresponding end portions 18 and 19 respectively which are substantially parallel to each other and rectangular in cross section as best seen in Figure 4.

The member 20 is preferably formed of sheet metal and is bent to form a rectangular portion 21, the opposite ends of which extend downwardly and inwardly at their adjacent ends as best seen in Figure 5, to form the holder 22. The portion 21 is adapted to be mounted on the end 19, and portion 22 is adapted to receive the head 23 of a razor blade 24.

Referring to Figure 6 the sheet metal member 25 is bent to form the rectangular portion 26, the opposite ends of which extend outwardly in parallel spaced relationship to form the portion 27. The width of portion 27 tapers from its wide end 28 to its narrow end 29. Portion 26 of member 25 is mounted on end 18 with the end 28 thereof abutting portion 16 as best seen in Figure 1.

With the device thus assembled as seen in Figure 1 the edge 30 of the blade 24 extends into the space between the flanges forming the portion 27. The tapered edges of these flanges are beveled on their outer sides to form cutting edges. By moving fingerholds 14 and 15 away from each other ends 18 and 19 will be moved away from each other exposing most of the edge 30 as seen in Figure 2. The portion 28 being of sufficient width to remain in engagement at all times with blade 24 to form a guide therefor. As ends 18 and 19 move toward each other the edge 30 will move into engagement with the space formed in portion 27; the portion 27 being tapered to cause a gradual engagement and a scissors type cutting effect. The adjacent edges of portion 27 cooperate with edge 30 to form the cutting surface.

In Figure 3 member 20 is shown reversed on end 19 so that blade 24 extends away from end 18 to provide a knife. This is done by removing member 20 turning it through an arc of 180° and applying it again.

In Figures 7, 8, 9, and 10 a modification of the

invention is shown, wherein member 20' is provided with a flange 31 which extends downwardly from one end of portion 22' and rests against one side of the blade 24 terminating short of its edge 30. The member 25' has the rectangular portion 26' but portion 27 is replaced by a tapered flange 32 having its wider end flared outwardly at 33. The flange 32 engages against the opposite side of blade 24 with the wide portion 10 33 constantly in engagement with the blade 24 to guide it. The edge 34 of flange 32 cooperates with edge 30 to form the cutting surface and flange 31 is under tension to hold blade 24 tight against flange 32.

15 The members 18 and 19 are provided with longitudinal recesses 35 to receive the rounded top of head 23. The members 20 and 25 can be mounted on either of the ends 18 and 19.

While the device has been illustrated with a 20 single edge blade, it is also well adapted for use with a double edge blade by slight modification of portion 22 so that one edge of the blade can be clamped therein.

It is to be understood that the drawings and 25 description are intended to illustrate only a preferred embodiment of the invention, the right being reserved to make such changes and modi-

fications as do not depart from the spirit and scope of the invention as hereafter claimed.

I claim as my invention:

A scissors comprising a shear frame including a pair of pivotally connected handle members, portions formed integral with and disposed at an angle to said handle members, said portions projecting in opposite directions to aline in one position, polygonal shaped shanks formed integral with said portions and projecting therefrom substantially at right angles thereto, said shanks being parallel when said portions are alined; a frame including a portion shaped to closely engage one of said shanks, said portion terminating in spaced jaws, adapted to engage the head of a safety razor blade, and provided with inturned free edges to retain the head in engagement with the jaws; and a second frame including a portion shaped to closely engage said other shank, spaced blade elements formed integral with and projecting from the shank engaging portion to receive the cutting edge of the razor blade, the free edges of said blade elements being beveled on their outer sides and tapered toward their outer ends to form cutting edges to co-act with the razor blade.

BYRON L. ATCHISON.
